REFRIGERATED MEAT DISPLAY CASE

Max O. Cullen, 439 Clinton Place, River Forest, Ill.

Filed Nov. 3, 1964, Ser. No. 82,455

Term of patent 7 years

(Cl. D80—11)

FIG. 2 is a top plan view thereof.

FIG. 3 is a rear elevational view of FIG. 1.

FIG. 4 is an elevational view taken from one end thereof, the opposite end being the same as the end shown.

I claim:

The ornamental design for a refrigerated meat display case, as shown.
